CLAIM

The ornamental design for a door lock set installation jig, substantially as shown and described.

DESCRIPTION

FIG. 1 is a perspective view of a door lockset installation jig in accordance with the present invention.

FIG. 2 is a side elevation view of the door lockset installation jig of FIG. 1.

FIG. 3 is a top elevation view of the door lockset installation jig of FIG. 1.

FIG. 4 is a side elevation view of the door lockset installation jig of FIG. 1.

FIG. 5 is a rear elevation view of the door lockset installation jig of FIG. 1.

FIG. 6 is a bottom elevation view of the door lockset installation jig of FIG. 1; and,

FIG. 7 is a front elevation view of the door lockset installation jig of FIG. 1.

The broken line showing is for illustrative purposes only and forms no part of the claimed design.
